UNITED STATES PATENT OFFICE

WILLIAM P. HORNBUCKLE AND ROBERT F. CRAIG, OF STANLEY, NORTH CAROLINA

DRYING AND EXTRACTING MACHINE

Application filed March 26, 1931. Serial No. 525,516.

This invention aims to provide a simple means whereby the yarn on a beam or a package holder of a dyeing machine may be dried, the construction being such that the beam or package holder can be taken out of the dyeing machine, with the yarn or other material on the beam or package holder and can be placed in the device forming the subject matter of this application, so that the yarn can be dried directly on the said beam or package holder upon which it has been dyed.

A practice heretofore has been to unwind the yarn from the beam or packages and then dry the yarn, a practice which is fraught with much difficulty and expense, and thus considerable time is consumed, and for the further reason that the yarn is almost certain to be tangled or knotted during the removal of the yarn from the beam or package holder, and in the preparation of the yarn for dyeing, in the device forming the subject matter of this application, it is necessary merely to remove the beam or package holder from the dyeing machine and to place the same in the device forming the subject matter of this application, the valves being opened to permit the heated air to pass into the beam or package holder and outwardly through the yarn on the beam or package holder, or if desired, if the heated air should not be required, then the device can be operated either to force air through the beam or package holder or to draw air through the same by reversing the mechanism.

This invention aims to provide a simple mechanism for forcing heated air through beams or package holders having yarn thereon which has been dyed, bleached, or otherwise treated with liquid by providing simple means whereby the yarn holders can be placed into the device and heated air forced therethrough after the said yarn holder has been placed in position, and in case a beam is used the upper end of the beam is closed by means provided in the device, while in the case of a package holder, no means are required for holding the same in place or closing the upper end thereof as this is already done on account of the peculiar construction of the package holder, but if desired, if great

pressure was exerted on the package holder suitable holding means such as shown, for the beam can be employed for the package holder for the screw which is shown can be moved downwardly to a point where the lower end of the screw mechanism will engage the upper end of the package holder should it be desired to hold the same in position, but ordinarily the weight of the package holder itself will be sufficient to hold the same in place.

Some of the objects of the invention having been stated, other objects will appear as the description proceeds when taken in connection with the accompanying drawings, in which—

Figure 1 is a side elevation with the floor portion in cross-section showing an embodiment of the invention;

Figure 2 is an enlarged detailed view partly in cross-section taken along the line 2—2 with the lower portion thereof shown in cross-section;

Figure 3 is an enlarged detailed view of the lower left-hand portion of Figure 2;

Figure 4 is an enlarged detailed view partly in cross-section of the lower portion of the package holding unit shown in the left central portion of Figure 1;

Figure 5 is a plan view of one of the end members of the beam.

Referring more particularly to the drawings, the numeral 10 indicates an electric motor preferably of the reversible type which has a pulley 11 thereon on which a belt 12 is mounted, said belt being mounted on a pulley 13 on a blower 14 and from this blower, pipe 15 leads to a drier 16, this drier being a mechanism having heated members herein for heating the air as it is passed therethrough and this drier is supported by a platform 17. Extending from the other end of the drier is a pipe 18 which is connected to a T 19, said T 19 having pipes 20 and 21 extending in opposite directions therefrom with a plurality of T's 22, 23, 24, and 24a secured therein and at each end of this pipe 20 and 21 there are elbows 25 and 26, and valves 27, 28, 29, 30, 31 and 32 are secured to these T's and elbows, and secured to the upper ends of these valve members are the

seat members 33, 34, 35, 36, 37, and 38. These members 33 to 38 project through a floor or platform 39 and have a circular lead seat 40 on the upper surface thereof onto which a beam head 41 on beam 42 is adapted to fit with said beam head 41 having a portion 43 which is adapted to coincide with the lead seat 40 and also the lower portion of a package holder 44 has a circular portion 45 which is also adapted to fit on the lead seat 40. This package holder has a plenum chamber 46 with a plurality of perforated pipes 47 extending upwardly therefrom with bolts 48 around the periphery thereof and a central bolt 49 secured to the upper portion of the member 44 above the plenum chamber as at 50. These pipes 47 and bolts 48 and 49 project upwardly and are secured to a suitable head member 51 and these pipes are adapted to have placed thereon a plurality of packages of yarn 52. The beam member 42 is adapted to have wound thereon yarn 53, and the said beam member is hollow and at the upper portion thereof has secured thereto end member 55 which has a circular opening 56 through the upper end thereof with a circular flange 57 which is adapted to coincide with the lead seat 58 in a cap member 59, the cap member being adapted to be held by screw 63 over the upper end of the beam to close the same so as to cause the hot air to be forced outwardly from the interior of the beam through the yarn as the upper end is closed by the cap 59.

Secured to the platform or floor 39 and projecting upwardly therefrom are the supports 60 and 61 which are secured at their upper ends to a longitudinally disposed member 62 which has vertically disposed holes therethrough which are threaded to receive threaded screws 63 which have near the lower portion thereof a hand wheel 64, said hand wheel having an enlargement 65 on the lower end thereof which enlargement projects into a circular member 66 which is threaded to receive a nut 67 loosely secured on screw 63 to hold the member 66 onto 63. Member 66 fits into a circular cavity in the top of the member 59 so that when the screw 63 is moved downwardly by turning hand wheel 64 that the lead seat 72 in cap member 59 will be forced against the flange 57 to close the upper end of the beam.

The upper end of the package holder has a cap member or end member 51 secured thereon by means of the bolts 48 and 49 and this cap member is closed but has eyes 71 therein for handling the same.

The member 59 has eyes 72 for handling of the same. The trackway 73 is disposed above the mechanism with an overhead traveling hoist 74 mounted thereon, said hoist having a block and tackle arrangement 75 so that the hooks 76, only one of which is shown, may be hooked into the eyes 71 for

placing the package holder into this device or for removing it therefrom.

The upper end of the beam indicated by the reference character 55 has a spider member 77 therein and this spider member may be engaged by the hook or hooks 76 for placing it in the mechanism or withdrawing it therefrom.

The members 33 to 38 inclusive have a passageway 80 therethrough, which passageway in the case of the package holder registers with the passageway formed by the circular portion 45 and leads into the plenum chamber 46. The hot air is forced up through passageway 80 and through plenum chamber 46, goes up through the perforated pipes 47 and forced on through the yarn packages 52 on these perforated pipes. In the case of the beam, the passageway 80 leads into the end of the beam and passes through the passageway 81 in the end of the beam inside of the foraminous circular member 82 on which the yarn is wound on the beam. The lower left-hand corner of the structure of the beam is shown in Figure 3 wherein the head member 41 has a groove 85 therein which is annular into which the foraminous material 82 projects and also a nickel-copper alloy sheet of material 86 projects into this and covers the yarn bearing surface of the end member of the beam, said member 86 being curved over the outer periphery of the end member and back onto the back side of the end member where it projects into an annular groove 87 with lead or other suitable material being forced thereinto to hold the member 86 in position. Also lead is poured into the annular groove 85 to hold the foraminous member 82 and the member 86 in position. The end members of the beam are secured together by means of bolts 88 on which spacers 89 are placed and on these spacers 89 annular members 90 are secured, each of said annular members having a plurality of set screws 91 therein for adjusting the position of members 90 on spacers 88.

In the drawings and specification there has been set forth a preferred embodiment of the invention, and although specific terms are employed, they are used in a generic and descriptive sense only, and not for purposes of limitation, the scope of the invention being set forth in the appended claim.

We claim:

In a yarn treating machine, a framework, a seat member having a passageway therein, said seat member being adapted to receive the lower end of a package of yarn, a cap for closing the upper end of the package of yarn, said cap member having a pair of handle members on the upper side thereof, a screw mounted for vertical movement in the upper portion of said framework, a hand wheel integral with said screw, an enlargement on the lower end of said screw, a pressure mem-

ber having an interiorly threaded opening in the upper side thereof adapted to receive the lower end of said screw, a nut loosely surrounding said screw and being adapted to be secured in said interiorly threaded opening to secure said pressure member onto said screw, the lower face of said pressure member being adapted to fit into said cavity in said cap member to press against said cap member to close the upper end of the package of yarn and to hold the lower end of the package on said seat member.

In testimony whereof we affix our signatures.
